S. HICKEL

SHOE FORM

Filed Sept. 15, 1924

*Inventor
Samuel Hickel
by his Attorneys
Baldwin Wright*

UNITED STATES PATENT OFFICE.

SAMUEL HICKEL, OF CHARLESTON, WEST VIRGINIA.

SHOE FORM.

Application filed September 15, 1924. Serial No. 737,771.

To all whom it may concern:

Be it known that I, SAMUEL HICKEL, a citizen of the United States, and resident of Charleston, in the county of Kanawha and State of West Virginia, have invented certain new and useful Improvements in Shoe Forms, of which the following is a specification.

My invention relates to a device for stretching or forming a shoe so that pressure will not come on the foot at points where there are corns or bunions. It also enables the shoe to be raised at the toe or at places where there are seams to prevent undue pressure upon the foot at these places.

An object of the invention is to provide such a device which will be simple in its construction but efficient in operation, and which will enable the shoe to be stretched at any desired point.

Further objects of the invention will be apparent from the following detailed description and appended claims.

In the drawings:

Figure 1 is a side view of the device with the parts in closed position.

Figure 2 is a side view of the device with the parts in open position and one part in position within a shoe.

Figure 3 is a transverse section of the device in operative position with relation to a shoe.

Figures 4, 5 and 6 are perspective views of some of the forms of members that may be employed for stretching portions of the shoe.

The invention comprises two members 1 and 2 hinged together at 3 with handles 4 and 5 respectively. The member 1 is slightly smaller than the member 2 so that it will fit within the other when the parts are closed as in Figure 1. This member 1 is preferably made of spring steel or some other metal which has considerable resiliency. Both members 1 and 2 are of generally inverted trough shape. The outer member 2 is heavier and stiffer than the inner member and may be made of some heavy metal.

The member 1 is provided with holes in which will fit the stems 6 of forms 7, 8 and 9, as shown in Figures 4, 5 and 6, respectively. These forms are given various shapes according to the purpose for which

each is to be used. A round corn or bunion at the side of the foot will be represented by 55 the form 9, while if it is desired to stretch the shoe over the top seam near the toes, a form 8 as shown in Figure 5 may be employed. Special forms may be designed for special purposes and for individual cases. 60

The outer member 2 is preferably provided with depressions 10 corresponding generally to the position of the various forms to be employed. In using the invention, the desired forms are placed in the 65 member 1 which is then inserted into the shoe A as indicated in Figure 2. By pressure on the handles, the outer member 2 will be forced down over the shoe and inner member, and the forms will force the leather 70 of the shoe outward into the depressions 10. The parts may be retained in this position for as long a time as is necessary to properly stretch or form the shoe. When removed, the shoe will retain to a great extent the 75 contour given it, and therefore will not bear with much force against the points where the forms have been thus relieving the foot from pressure at these places.

It is obvious that in this manner a shoe 80 may be easily treated to render it comfortable to the wearer even if corns or bunions are present or if the shoe is too tight across any particular portion of the foot. The size and precise contour of the forms may be 85 varied and the materials of which the device is constructed are also capable of wide variation. In general it is to be understood that the invention is limited only by the scope of the appended claims. 90

I claim as my invention:

1. A shoe form comprising two members pivotally connected with each other and each having a handle portion, one of said members having a convex outer contour and being provided on opposite sides and on its upper side with detachable form pieces, while the other member has a concave inner side formed with depressions adapted to receive said form pieces. 95

2. A shoe form comprising two members pivotally connected with each other and each having a handle portion, one of said members being resilient and carrying one or more detachable form pieces while the other member which is rigid is formed with one or 100

more depressions to receive said form pieces.

3. A shoe form comprising two members pivotally connected with each other and each having a handle portion, one of said members which is of concavo-convex contour is resilient and carries one or more detachable form pieces while the other member

which is rigid or non-resilient is shaped to receive the resilient member and is formed with depressions to receive the form pieces.

10

In testimony whereof I have hereunto subscribed my name.

SAMUEL HICKEL.
